Primary Examiner—Jeffrey Asch

[57] **CLAIM**

The ornamental design for a rack for dispensing screen cloth, as shown and described.

DESCRIPTION

FIG. 1 is an isometric view of the rack for dispensing screen cloth which comprises this invention;
FIG. 2 is a front view of the rack of FIG. 1;
FIG. 3 is a rear view of the rack of FIG. 1;
FIG. 4 is a top view of the rack of FIG. 1;
FIG. 5 is a bottom view of the rack of FIG. 1; and
FIG. 6 is a right side view of the rack of FIG. 1;
FIG. 7 is a left side view of the rack of FIG. 1; and,
FIG. 8 is an isometric view of a second embodiment of the rack for dispensing screen cloth equipped with a hand crank drive mechanism rather than an electric drive mechanism.
